E. Schenck

UNITED STATES PATENT OFFICE.

ROBERT HEAD, OF YONKERS, NEW YORK, ASSIGNOR TO THE AEOLIAN COMPANY, A CORPORATION OF CONNECTICUT.

TRANSPOSER FOR AUTOMATIC PIANOS AND THE LIKE.

Application filed August 19, 1920, Serial No. 404,509. Renewed May 1, 1922. Serial No. 557,783.

To all whom it may concern:

Be it known that I, ROBERT HEAD, a citizen of the United States, residing at Yonkers, Westchester County, New York, have invented new and useful Improvements in Transposers for Automatic Pianos and the like, of which the following is a specification.

My present invention relates to improvements in transposers for automatic pianos and the like. It accurately effects the transposition of the music to the desired key and then automatically locks and maintains the parts in their then position throughout the playing of the given music-roll unless intentionally changed or released. However, the transposer is automatically released to change the parts back to normal every time a new roll is played, thereby preventing a succeeding roll from being inadvertently played in a key which is wrong for it although right for the preceding roll.

These and other features and advantages of my improvements will be appreciated by those skilled in the art from an understanding of the following description in connection with the drawings. These purport to illustrate only one of the specific embodiments my invention is adapted to take:—Fig. 1 being a fragmentary front elevation of the music-roll box and related parts of a player-piano embodying my invention; Fig. 2 is a plan view partly in horizontal section on the line 2—2 in Fig. 1; Fig. 3 is a front elevation of the tracker-board and my device on an enlarged scale; Fig. 4 is a view looking upwardly at the devices shown at the right in Fig. 3; Figs. 5 and 6 are vertical views respectively on the lines 5—5 and 6—6 in Fig. 3 looking in the direction of the arrows; and Fig. 7 is a rear elevation of the tracker-board with my devices—for simplicity, said figure omitting showing the tracker tubes or ducts.

Describing now the devices of the drawings.—1 is the music-roll box of a player-piano, 2 is a music-roll and sheet in playing position; 3 is the take-up spool; 4 is my improved tracker-board; 5 is the air-motor for driving the music-roll; 6 is the lever for operating the clutch 7 so that the motor 5 can be caused to drive the take-up spool 3 to draw the perforated music-sheet downwardly over the tracker-board to play it, this being the condition shown in Fig. 1; or vice versa when the clutch-member 7 is slid to

the right in Fig. 1, said motor is made to drive the spool of the music-roll and thereby rewind the music-sheet back on to said spool.

For the above purposes the following well known arrangement is provided comprising sprocket-wheel 8 on the air-motor crank-shaft 9, driving by chain 10 a sprocket-wheel 11 on a clutch-shaft 12 on which is loosely mounted another sprocket-wheel 13 connected by chain 15 with a sprocket-wheel 16 on the drive-trunnion music-roll shaft 17. 14 is a clutch-pin on the hub of the sprocket-wheel 13 adapted to be engaged by the clutch-pin 18 on the clutch-member 7, splined to the shaft 12 by 70 the spline 19 so as to be rotatable with said shaft but slidably thereon by the lever 6 pivotally supported at 20 so as to carry the clutch-pin 18 into and out of rotary clutch-engagement with the pin 14. The aforesaid 75 clutch-member 7 has an annular groove in which the upper end of the lever 6 is seated. Further, it is provided with the pinion 21 adapted to be brought into and out of mesh with the gear-wheel 22 on the drive shaft 23 80 of the take-up spool 3. The clutch-lever 6 is operated through a link 24 from a finger-piece at the key-slip of the piano and which obviously it is not necessary to illustrate, or automatically from a perforation in 85 the music-roll in the well-known manner.

My tracker-board comprises a stationary part 4 provided with pedal-operating ducts 25, 26, 27 and theme-accenting ducts 28 and 29 at its ends. It is also provided at each 90 end on a line above the aforesaid ducts with dynamics-controlling ducts 30. For the entire length of said part 4 of the tracker-bar between the aforesaid right and left-hand sets of ducts, said part 4 is 95 cut away by a long, wide, rectangular opening 31. This opening has narrower extensions 31^a from its ends in line with the aforesaid ducts 25, 26, 28, 29, 27 and underneath the dynamics-ducts 30.

32—32^a is the endwise slidable or transposable part of the tracker-bar operatively supported within the described opening 31^a—31—31^a in the stationary part 4 of the tracker-bar. This slidable part 32^a—105 32—32^a has the same form as the opening 31^a—31—31^a except that its wide part 32 is not so long as the wide part of the opening 31 to permit said part 32^a—32—32^a to be slid endwise in said opening 31^a—31—31^a. 110

The ⁵slidable part 32^a—32—32^a is provided with the usual row of note-operating ducts 33, these being in line with stationary ducts 25, 26, 28, 29, 27. From Figs. 1 and 3 it will be seen that this ¹⁰slidable part of the tracker-bar can be shifted from its central position four note-ducks to the left and four to the right, which gives a range of transposition of eight tones, of the notes of the music-roll. If desirable, this range could be of course increased by making the parts 32^a—32—32^a longer so as to include more note-ducks.

From Fig. 5 it will be noted that the ¹⁵part 32^a—32—32^a is rabbeted into the opening 31—31—31 in the stationary part of the tracker-bar, and that the ²⁰slidable mounting of said part 32^a—32—32^a is completed by the lugs 34 (Figs. 5 and 7) on the back of said part overlapping the part 4.

I will next describe the means for giving the ²⁵movable part 32^a—32—32^a a step-by-step adjustment in either direction from its central position to effect the desired transposition, each step being equal to the distance between centers of any two adjacent note-ducks. After this adjustment has been made, the drag of the tracker-tubes, etc., on the ³⁰movable part of the tracker-bar may disturb it, and I provide automatic locking means which prevents this. Further, I provide that this locking means may be directly released at any time, or in any event will be always released automatically on ³⁵rewinding the music-roll.

The foregoing means comprise the following:—35 (Figs. 4 and 7) is an elongated member screwed to the back of the ⁴⁰slidable part 32 of the tracker-bar and provided with two sets of right and left ratchet-teeth 36 and 37 (Fig. 4) between which is the non-toothed space 38. 39 is the operating handle of the transposer, pivotally supported at 40 on a bracket 41 screwed to the back of the ⁴⁵stationary tracker-bar part 4 and projecting forwardly to the front of the tracker-bar through a horizontally elongated slot 42.

When the ⁵⁰slidable tracker-bar part 32^a—32—32^a is in the center position, the non-toothed part 38 of its integral member 35 is located at the pivot 40 of the said handle 39.

The handle 39 has a flat fan-shaped rear end 39^a on which are mounted the pawls 43—43 by the pivots 60—60. The pawls have pins 43^a—43^a coacting with corresponding recesses in the rounded rear-end of the handle.

44—44 are a pair of elbow-levers pivoted at 45—45 to the bracket 41. 46 is a piece of ⁶⁰spring-wire bent into circular form with its ends secured to rear-ends of said elbow-levers, said spring therefore keeping the rear-ends of the elbow-levers apart and forcing their forward ends towards and into interlocking engagement with the ratchet-teeth

36 and 37 carried by the ⁶⁵slidable part of the tracker-bar.

52—52 are leaf-springs mounted on the elbow-levers and tensioned so as to bear away from said levers against the pawls 43 whose pins 43^a in Fig. 4 they keep seated in the recesses in the rounded rear-end of the handle 39. The spring 46 is more powerful than these leaf-springs so that it is not overcome by their action. ⁷⁵

Fig. 4 shows the ⁸⁰slidable tracker-bar part locked against unintentional displacement in its middle position (relative to the stationary part 4 of the tracker) by the forward ends of the elbow-levers 44 engaging the aforesaid ratchet-teeth 36 and 37.

As soon as it is unlocked in any of its transposed positions, the ⁸⁵slidable tracker part 32^a—32—32^a is automatically returned to its central, untransposed position by means as follows:—47 (Fig. 7) is a pin on the back of said ⁹⁰slidable part at its longitudinal center; and 48 is another adjacent pin on the fixed tracker part 4 at the longitudinal center of the opening in which the ⁹⁵slidable tracker part slides. 49—49 are a pair of separate plates with elongated rectangular openings therein hooked over the aforesaid pins 47—48. Spiral tensioned springs 50—50 connect the outer ends of the plates 49—49 with pins 51—51 located towards the ends of the stationary part 4 of the tracker-bar.

When the handle 39 is rocked one, two, three or four times to the right and back each time to its middle position, it shifts to the left the ratchet-toothed member 35 and ¹⁰⁰slidable tracker part 32^a—32—32^a to the extent respectively of one, two, three or four ratchet-teeth and locks them there; in other words, accurately transposes the music-perforations in the sheet 2 to the extent of the same number of notes in the right hand or treble direction on the piano keyboard. ¹⁰⁵

In detail:—Rocking the handle 39 to the right moves the left-hand pawl 43 (Fig. 4) to the left, the adjacent leaf-spring 52 carrying it upwardly into the aligned ratchet-space; the continuing right-hand movement of the handle causing the pawl to slide the movable tracker part 32^a—32—32^a a trifle more than one ratchet-tooth to the left against the tension of the opposed spring 50 (described above in connection with Fig. 7). This causes the left-hand elbow-lever 44 in Fig. 4, impelled by the spring 46, to ride into the next adjacent ratchet space to the right. On the return movement of the handle 39, the aforesaid spring 50 takes up the slight lost motion by pulling the tracker part 32^a—32—32^a slightly to the right until the given ratchet-tooth abuts against the end of said left-hand elbow-lever 44. This insures that each vibration of the handle 39 gives a movement to the sliding tracker part which is exactly equal to one ratchet-tooth, which ¹¹⁵¹²⁰¹²⁵¹³⁰¹³⁵

in turn is designed to be exactly equal to the distance between centers of the adjacent note-ducks 33—33.

It will be seen from Fig. 4 that this movement of the tracker part 32^a—32—32^a could not be accomplished without the preliminary release of the right-hand elbow-lever 44 from its locking engagement with the rack 37. However, this takes place automatically during the first part of the right-hand movement of the handle 39, because the notched rounded end of said handle by bearing or abutting against the pin 43^a of the right-hand pawl 43 (Fig. 4) forces the free end 15 of said pawl downwardly against the spring 52 and swings the elbow-lever 44 out of its locking engagement with the rack 37. As the latter part of the right-hand movement of the handle 39, as above described, feeds the 20 tracker-bar and rack one tooth or step to the left, this same right-hand elbow-lever, impelled by the spring 46, enters into locking engagement with the next adjacent tooth to the right in the rack 37 in Fig. 4.

25 The springs automatically return the handle and parts to their Fig. 4 position.

In the same way, every complete right-hand vibration of the handle 39 effects the above cycle of operations and shifts the 30 tracker to transpose the music one note. The same is true for every left-hand vibration of the handle 39, the sole difference being that the transposition is in the opposite direction of the musical scale.

35 After the tracker has been shifted to effect the total designed number of transpositions, in either direction, it cannot be shifted any further in spite of continued operation of the handle, because then the toe of the given pawl 43, then in action, merely rides idly on the untoothed center portion 38 (Fig. 4) of the member 35.

The locking action of the elbow-levers 44 can be released at any time by the handle 46 39 as follows:—Assume, for instance, that the tracker 32^a—32—32^a has been shifted one or more teeth to the left from its center position shown in Fig. 4. Then the left-hand elbow-lever 44 will be holding it in 50 that position against the tension of the opposed spring 50 (Fig. 7) tending to pull the tracker to the right. It will be seen then that rocking the handle 39 to the left will release said active left-hand elbow-lever, whereupon said spring will be free 55 to pull the tracker part 32^a—32—32^a to the right until the end of the opening in its attached plate 49 (Fig. 7) strikes against the fixed centralizing pin 48, which means that the given spring 50 returns the tracker part to its central non-transposed position where it remains until readjusted by further operating the handle 39.

60 The following is also an important feature of my invention whereby after each roll

played with the tracker-bar transposed, the device automatically returns the tracker-bar to its central position. The reason and advantage of this is that many rolls do not need transposition and are spoiled by it, 70 or at any rate the roll about to be played will not ordinarily be properly transposed exactly like the roll that has just been played. For this reason, I provide for the automatic return of the tracker to normal 75 after each transposed roll played, by means as follows:—

55 (Figs. 1 and 2) is an arm secured fast to a vertical rock-shaft 56 supported in a bearing member 57 on the right side of the 80 music-roll box 1. Fast on the lower end of this rock-shaft is another arm 58 at right angles to the arm 55. The free end of said arm 58 is forked to straddle the clutch shaft 12 and engage the enlarged head 12^a on the 85 end of said shaft. 59 is a tension spring normally holding the arms 55 and 58 in the position shown in Fig. 2. When, the given music-roll has been played with the transposer in use, and the operator shifts the 90 clutch-lever 6 (Fig. 1) to carry the pin 18 of clutch sleeve 7 into engagement with the pin 14 to rewind the music-roll, the whole clutch-shaft 12 will be shifted slightly to the right so that its head 12^a, 95 pulling on the arm 58, forces the other arm 55 towards the rear-ends of the elbow-levers 44—44 (compare Figs. 2 and 4), whereby the lugs 55^a—55^a on said arm cam together 100 said rear-ends of the elbow-levers, thereby unlocking their front ends (Fig. 4) from the rack on the tracker part 32^a—32—32^a which is then instantly restored by the springs 50—50, etc., (Fig. 7) back to its 105 central non-transposed position. This accomplishes the foregoing purpose with its resulting advantages.

What I claim is:

1. In combination with an automatic player using perforated music-sheets, means 110 for adjusting a part of the player to transpose the music; and means for automatically restoring said part to a normal non-transposing position, said means being put into operation from the resetting of the instrument for another playing.

2. In combination with an automatic player using perforated music-sheets, means for adjusting a part of the player to transpose the music until said part is released; 120 means for releasing said part automatically operated from resetting the instrument for another playing and means for automatically restoring said part to a normal, non-transposing position.

3. In combination with an automatic player using perforated music-sheets, means for adjusting a part of the player to transpose the music until said part is released; means for rewinding the music-sheet; means 130

- automatically operated from said rewind for releasing said transposer part; and means for automatically restoring said part to a normal, non-transposing position.
6. In combination with an automatic player using perforated music-sheets, a movable part for transposing the music, two racks with oppositely directed teeth connected with said part; a vibratable handle having two pawls, one for each rack, for moving the transposer part in one direction or the other, depending on which pawl and rack is in operation two locking members spring-pressed into locking engagement with said racks, said pawls coacting with said members whereby moving the handle in either direction from a central position, brings one of the pawls into operative engagement with its rack and causes the other pawl to disengage the locking member from the other rack.
5. In combination with an automatic player using perforated music-sheets, a movable part for transposing the music; two racks with oppositely directed teeth connected with said part; a vibratable handle having two pawls, one for each rack, for moving the transposer part in one direction or the other, depending on which pawl and rack is in operation; two locking members spring-pressed into locking engagement with said racks, said pawls coacting with said members whereby moving the handle in either direction from a central position, brings one of the pawls into operative engagement with its rack and causes the other pawl to disengage the locking member from the other rack; and spring means normally keeping the pawls slightly spaced respectively from the locking members.
6. In combination with an automatic player using perforated music-sheets, a movable part for transposing the music; means which when unopposed returns said transposer part to a normal, non-transposing position; two racks with oppositely directed teeth connected with said part; a vibratable handle having two pawls, one for each rack, for moving the transposer part in one direction or the other; depending on which pawl and rack is in operation; two locking members spring-pressed into locking engagement with said racks, said pawls coacting with said members whereby moving the handle in either direction from a central position, brings one of the pawls into operative engagement with its rack and causes the other pawl to disengage the locking member from the other rack.
7. In an automatic player using perforated music-sheets, the combination of a movable part for transposing the music; means which when unopposed, returns said transposer part to a normal, non-transposing position; and means for giving said transpos- er part a step by step movement to effect transpositions and for releasably locking said part in any of its said positions.
8. In combination with an automatic player using perforated music-sheets, a movable part for transposing the music; means tending to restore the movable part to a normal, non-transposing position; a rack connected with said part; a member spring-pressed into releasable locking engagement with said rack; a vibratable handle; and a pawl operable by said handle into engagement with said rack to give it and the transposer part a step-by-step movement into various transposing positions.
9. In combination with an automatic player using perforated music-sheets, a movable part for transposing the music; two racks connected with said transposer part, the teeth of which are directed toward each other; a pivotally supported handle having two oppositely directed pawls for engaging the racks, said pawls being severally pivoted to said handle; two pivotally supported locking members extending adjacently to the pawls and both being spring-pressed into locking engagement with the racks; springs holding the pawls yieldingly spaced from the aforesaid adjacent locking members; and an abutment between each pawl and the handle whereby vibrating the handle to either side of a central position presses one pawl against the adjacent spacing spring and locking member, disengaging the latter from its rack and at the same time carries the other pawl into operative engagement with its rack.
10. In combination with an automatic player using perforated music-sheets, a movable part for transposing the music; two racks connected with said transposer part, the teeth of which are directed toward each other; a pivotally supported handle having two oppositely directed pawls for engaging the racks, said pawls being severally pivoted to said handle, two pivotally supported locking members extending adjacently to the pawls, said members having adjacent extensions away from the racks; spring means tending to force said extensions apart and to force the locking members into engagement with the racks; springs holding the pawls yieldingly spaced from said adjacent locking members; an abutment between each pawl and the handle whereby vibrating the handle to either side of a central position presses one pawl against the adjacent spacing spring and locking member, disengaging the latter from its rack and at the same time carries the other pawl into operative engagement with its rack; means which when unopposed restores the transposer part to a normal non-transposing position with the handle between the two racks; and means for pressing

together the extensions from the locking members to disengage the latter from the racks, said means being itself operated from the resetting of the instrument for another 5 playing.

11. In combination with an automatic player using perforated music-sheets, means for adjusting and releasably retaining a part of the player to transpose the music; and 10 means which when said part is released automatically restores it to a normal non-transposing position.

12. In combination with an automatic player using perforated music-sheets, means 15 for adjusting and releasably retaining a part of the player to transpose the music; automatic means which when said part is re-

leased, automatically restores it to a normal non-transposing position; and means for releasing said part put into operation by the 20 performing of another function in connection with the player.

13. In combination with an automatic player using perforated music-sheets, means for adjusting a part of the player to transpose the music; and means for automatically restoring said part to a normal non-transposing position, said means being put into operation by the performing of another 25 function in connection with the player. 30

In testimony whereof, I have hereunto set my hand this 13th day of August, 1920.

ROBERT HEAD.
